UNITED STATES PATENT OFFICE.

PETER R. WARREN, OF BOSTON, MASSACHUSETTS.

PAPER BOX.

1,168,353.

Specification of Letters Patent. Patented Jan. 18, 1916.

Application filed April 13, 1915. Serial No. 21,147.

To all whom it may concern:

Be it known that I, PETER R. WARREN, a citizen of the United States, residing at Boston, county of Suffolk, State of Massachusetts, have invented a certain new and useful Improvement in Paper Boxes, of which the following is a specification, reference being had therein to the accompanying drawings.

10 This invention relates to a new and useful improvement in paper boxes and has special reference to that class of paper boxes which are employed as a display container for smaller boxes.

15 One object of the invention is to provide a box formed from a single blank of cardboard and capable of being printed on one side only, which shall have a partition formed integral with the box so that two or 20 more tiers or stacks of boxes may be separated from each other and be supported at the back as well as front, thereby preventing displacement as part of the boxes are sold or removed.

25 Another object of the invention is to make the box of a single sheet of paper died out and in such form that it may be folded up into the box with its flaps securely locked without the use of paste or adhesive of any 30 kind so that the blanks may be shipped or stacked away in flat unfolded sheet form and each blank as it is desired may be quickly folded and set up ready for use.

The invention will be fully understood 35 from the following description taken in connection with the accompanying drawings and the novel features thereof will be pointed out and clearly defined in the claims at the close of the specification.

40 In the drawings,—Figure 1 is a plan of a blank formed of a single sheet of paper ready to be folded into a box embodying the invention. Fig. 2 is a perspective view of the box shown in Fig. 1 folded and set up. 45 Fig. 3 is a transverse section of the folded box shown in Fig. 2. Fig. 4 is a plan of a portion of the box shown in Fig. 2, the left-hand end portion thereof being broken away as the construction is fully illustrated by 50 the parts shown.

Referring now to the drawings,—the blank is cut out and creased so as to form the main body portions 5, 6, 7, 8, 9, said blank being scored or creased as shown by 55 the dotted lines along the dividing lines be-

tween said body portions to facilitate the folding. Said body portions 5, 6, 7, 8, 9 form the sides and bottom of the folded box. The body or panel portion 5 has at each end thereof an extension flap divided 60 into two parts 10, 11 by a crease or score line 12 for the purpose to be hereinafter described. The body or panel portion 6 has at each end an extension forming a flap 13 which is separated from the combination 65 flap 10, 11 by a slit 14. The body or panel portion 8 has at each end an extension which is divided by a crease or score line 15 to form two portions 16, 17. The blank is creased along the dividing lines between 70 said body or panel portions and the end flap portions so that the end flap portions can be folded at right angles to the ends of said body portions. The panel portion 9 is formed with a slit 18 along the folding line 75 between said portion 9 and portion 8 and extending for a considerable portion of the length of said portion 9 but not for the entire length and is also formed with the two slits 19, 20 extending at right angles 80 to said slit 18 at the ends thereof in a transverse direction of the portion 9 and for a portion only of its width, preferably for about half its width.

When the blank is folded into the box 85 form the panel 5 forms one vertical side of the box, panel 6 forms the real bottom of the box, the panels 7 and 8 form a double wall for the other vertical side of the box and the panel 9 forms a false bottom for 90 the box with an intermediate partition formed by turning up the portion 21 along the crease line 22. The flap portions at the ends of the said body or panel portions 5, 6, 8 are bent to form end walls and tuck 95 flaps.

In setting up the box the panels 5 and 7 are first turned up along the folding or score lines 23, 24 respectively parallel with each other and at right angles with the portion 6, leaving the end flaps still in the extended form. Then the panel portion 8 is folded along the line 25 turning it down against the inner face of the panel portion 7 and the panel portion 9 is folded along the 105 line 26 at right angles to the vertical wall 8 so as to lie flat upon the inner face of the bottom 6, thus forming an interior false bottom and the tongue portion 21 formed by the slits 18, 19, 20 is turned up along the 110

crease line 22 into vertical position, as shown in Fig. 3, forming a longitudinal vertical partition along the middle of the bottom of the box for a considerable portion 5 of the length of the box. The flap portion 16 is then bent along its crease line 27 to form one end of the box and the portion 17 of the flap is then bent along the crease line 15 to lie against the inner face of the side wall 5. Then the flap portion 13 is turned up along the crease line 28 into vertical position outside of the flap portion 16. Then the flap portion 10 is bent along its crease line 29 against the outer face of the flap portion 13 and the portion 11 is bent along the crease line 12 and tucked in between the ends of the double wall formed by the panels 7, 8, thus forming a locking tongue. The flaps at each end are folded and tucked in in this manner and thus form a completely folded and set up box, as shown in Fig. 2.

It is obvious that the end flap portions 10 and 16 may be folded in reverse order to 25 each other, if desired, so that instead of the flap portion 16 forming the inner thickness of the end wall the flap 10 may form the inner thickness of the end wall while the flap 16 forms the outer thickness and the flap portion 17 would be used as the tuck flap. When the box or container is thus set up as shown in Figs. 2 and 3 the partition 21 divides the container into two compartments lengthwise of the container and a row of 35 smaller boxes may be placed in each compartment, the proportions and size of the container being planned with relation to the size of the boxes which it is to hold so that the width of each compartment will be equal 40 to the width or length of each one of the smaller boxes which the container is to hold. Thus the partition 21 forms a support or back stop for the tier of boxes in each compartment.

45 It is to be noted that all of the exposed portions of the container when set up are on the same side of the unfolded blank so that it is necessary to use a stock coated on only one side of the paper, and that the printing 50 or ornamentation is all placed on the same side. All portions of the other face of the blank will be concealed when the box is set up.

What I claim is:

55 1. A paper box or container having two side walls, two end walls and a bottom made of a single sheet of material, one of said side walls being formed of two panel portions folded on the line between them with 60 the fold on the upper edge and forming a pocket between them open at each end, the other side wall having flap extensions at both ends which are bent to form the outer faces of the ends of the box and terminate 65 in tuck flaps which are inserted in the ends

of the pocket between the two panels of the double side wall thereby locking the container in set up form.

2. A blank for a folding paper box container consisting of a single sheet of paper die cut and creased to form five body panel portions in such manner that one of the intermediate panel portions forms the real bottom of the box, one of the portions adjacent to one edge of said bottom forming 75 panel forms one side of the box, another panel portion immediately adjacent to said bottom portion forms an outer wall of the other side of the box, another panel portion adjacent to said outer side wall portion 80 forms an inside facing for said outer wall, another panel portion adjacent to said inside facing member forms an inside or false bottom for the container, said false bottom being slit to form a tongue portion which 85 can be bent up to form a vertical partition wall to divide the container into two compartments, and end forming flaps integral with some of said side body flaps which form the ends of the container. 90

3. A blank for a folding paper box container consisting of a single sheet of paper die cut and creased to form five body panel portions in such manner that one of the intermediate panel portions forms the real 95 bottom of the box, one of the portions adjacent to one edge of said bottom forming panel forms one side of the box, another panel portion immediately adjacent to said bottom portion forms an outer wall of the other side of the box, another panel portion adjacent to said outer side wall portion forms an inside facing for said outer wall, another panel portion adjacent to said inside facing member forms an inside or false bottom for 100 the container, said single side wall portion and said bottom body portion being formed with extension flaps at each end thereof which may be folded to form end walls of the set-up carton, the outer portion of said 110 extension flaps of the single side wall portion forming tuck flaps which are folded and tucked in between the ends of the two members of the double side wall to lock the container in set-up form. 115

4. A blank for a folding paper box container consisting of a single sheet of paper die cut and creased to form five body panel portions in such manner that one of the intermediate panel portions forms the real 120 bottom of the box, one of the portions adjacent to one edge of said bottom forming panel forms one side of the box, another panel portion immediately adjacent to said bottom portion forms an outer wall of the other side of the box, another panel portion adjacent to said outer side wall portion forms an inside facing for said outer wall, another panel portion adjacent to said inside facing member forms an inside or false 125 130

bottom for the container, said single side wall portion and said bottom body portion and said inside member of the double side wall being formed with extension flaps at 5 each end thereof which form end walls of the set-up carton, the outer portion of the said extension flaps of the single side wall portion forming tuck flaps which are folded and tucked in between the ends of the two

members of the double side wall to lock the 10 container in set-up form.

In testimony whereof I affix my signature, in presence of two witnesses.

PETER R. WARREN.
